(57) **CLAIM**

The ornamental design for a gemstone, as shown.

DESCRIPTION

FIG. 1 is a bottom view of the gemstone according to a first embodiment;

FIG. 2 is a right end view of the gemstone according to the first embodiment;

FIG. 3 is a front view of the gemstone according to the first embodiment;

FIG. 4 is a left end view of the gemstone according to the first embodiment;

FIG. 5 is a rear view of the gemstone according to the first embodiment;

FIG. 6 is a perspective view of the gemstone according to the first embodiment;

FIG. 7 is a top view of the gemstone according to the first embodiment;

FIG. 8 is a bottom view of the gemstone according to a second embodiment;

FIG. 9 is a right end view of the gemstone according to the second embodiment;

FIG. 10 is a front view of the gemstone according to the second embodiment;

FIG. 11 is a left end view of the gemstone according to the second embodiment;

FIG. 12 is a rear view of the gemstone according to the second embodiment;

FIG. 13 is a perspective view of the gemstone according to the second embodiment;

FIG. 14 is a top view of the gemstone according to the second embodiment;

FIG. 15 is a bottom view of the gemstone according to a third embodiment;

FIG. 16 is a right end view of the gemstone according to the third embodiment;

FIG. 17 is a front view of the gemstone according to the third embodiment;

FIG. 18 is a left end view of the gemstone according to the third embodiment;

FIG. 19 is a rear view of the gemstone according to the third embodiment;

FIG. 20 is a perspective view of the gemstone according to the third embodiment; and,

FIG. 21 is a top view of the gemstone according to the third embodiment.
